ATTORNEY

UNITED STATES PATENT OFFICE.

HENRY C. RIESBOL, OF NEW YORK, N. Y.

CONCRETE BUILDING FORM.

Application filed November 17, 1924. Serial No. 750,410.

To all whom it may concern:

Be it known that I, HENRY C. RIESBOL, a citizen of the United States, residing at New York city, in the county of New York and State of New York, have invented new and useful Improvements in Concrete Building Forms, of which the following is a specification.

This invention relates to improvements in concrete building forms for the construction of concrete walls formed with vertical ribs on the inside face thereof, whereby the rib is formed simultaneously with the forming of a wall.

Another object of the invention resides in the provision of a plurality of channel members adapted to be held in vertical position by a form and which form co-acts with the channel members for forming the ribs on the wall and to which the laths are attached for supporting the plaster in spaced relation with the wall, whereby air space is provided between the wall and the plaster to prevent the condensation of a wall from contacting with the plaster which often results in the cracking and spoiling of the same.

Another object of the invention is to provide an improved means in the assembling and disassembling of concrete wall forms which is simple in construction, cheap of manufacture and which will reduce the cost of labor in the use of the form to a minimum.

A still further object of the invention resides in the provision of a form and a supporting structure therefor which is adapted for use in the pouring of walls of one story in height whereby the cost of the scaffolding now employed for this purpose is greatly reduced.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a horizontal sectional view showing a plurality of rib forming members in position for the forming of a concrete wall.

Figure 2 is a similar view but showing the wall in its completed condition.

Figure 3 is a detail sectional view on the 55 line 3—3 of Figure 1.

Figure 4 is a detail perspective view of one of the rib forming members.

Figure 5 is a fragmentary sectional perspective view of a portion of the finished 60 wall structure.

Referring more particularly to the drawing, the reference numeral 10 designates a metallic channel member which is U-shaped in horizontal section and which is formed with outwardly extending flanges 11. Any number of channel members may be employed in the construction of a wall, the amount depending upon the length of the 70 wall and the distance desired between the ribs which are to be formed on the wall. In use, the members are placed upright in a vertical position and held therein by a form 12 into which the concrete is poured.

The form 12 comprises an outer section 75 13 and an inner section 14 which are held in spaced relation by brace rods 15. The outer section 13 includes a horizontal liner 16 any number of which may be provided and arranged in spaced relation and which 80 engage vertical beams 17 carried by the wall forming sections 18. The sections 18 are arranged in intimate contact with each other to form the outer wall of a mold cavity 19 formed at the space between the 85 outer and inner sections 13 and 14.

The inner section 14 includes a plurality of inner wall forming sections 20 between the meeting edges of which one of the channel members 10 is arranged. The ends of 90 the sections 20 abut the flanges 11 which prevent movement of the sections toward the outer section 13. The sections 20 are held in position by a horizontal liner 21 which is supported by brackets 22 carried by the channel members 10. Any number of these liners may be employed, but for the ordinary height of wall, three have been found to be sufficient. The liners 16 and 21 are held tight against the inner and outer wall forms by wires 22 which are looped about the liners and twisted as at 95 23 for a distance approximating the thickness of the wall to be formed.

Additional means is provided for holding 105 the outer sections 18 in vertical position which includes bolts 24 which extend through openings 25 in the body portion of

the channel members and which extend into the cavity 19. The bolts are inserted at suitable points along the length of the channel member and each receives a nut 26 upon its threaded end. Each nut is formed with an eye 27 to which the free ends of a wire 28 are connected, the wires extending through the outer wall sections and around the meeting beams 17.

10 The channel members removably support wood inserts 29 which are arranged on the inside thereof and are adapted to be embedded in the ribs of the wall during the formation of the same and which inserts 15 are formed with anchoring elements 30 which securely hold the inserts embedded.

20 After the parts just described have been assembled the reinforcing rods 31 are placed in the mold cavity to extend both horizontally and vertically and are arranged in suitable spaced relation. The wall form is now ready to receive the concrete, after which the form is left in position until the concrete has ample time to set.

25 When removing the form after the formation of the wall, the wires 22 and 28 are clipped adjacent the surface of the wall to permit the liners 16 and 21 to be removed, after which the bolts 24 are unscrewed from 30 the nuts 26, thereby leaving the nuts, bolts and the wires 28 in the wall structure. The securing elements which connect the wood inserts with the channel members are now removed as are the sections 20. This now 35 leaves the channel members free whereby the wall is clear of any form structure, it being understood that the outer wall forming sections 18 have been previously removed with the liners 16 after the severing 40 of the wires 22 and 28.

Figure 2 of the drawing clearly shows the wall structure in its completed condition wherein it will be noted that the brace rods 15, the twisted portions 23, portions of the wire 28 and the nuts 26 are left in the wall to co-operate with the reinforcing rods 31 for adding strength to the same and the saving of time in the removal of the form. It will be seen that the channel members 45 serve to form spaced ribs 32 on the inner surface of the wall designated by the numeral A wherein the wood inserts are embedded, and to which furring strips are secured and to which strip laths are fastened 50 for receiving the inner plaster 33. The ribs 32 serve to space the plaster from the wall proper whereby air is free to circulate, it also being found useful for the passage of electric wires when wiring the building for 55 electricity.

60 While I have described what I deem to be the most desirable embodiment of my invention, it is obvious that many of the details may be varied without in any way departing from the spirit of my invention,

and I therefore do not limit myself to the exact details of construction herein set forth nor to anything less than the whole of my invention limited only by the appended claims.

70 What is claimed as new is:—

1. A building form including a plurality of spaced channel members, inner wall forming sections between said channel members, and means on said channel members for removably supporting a horizontal beam for holding said channel members in alignment.

75 2. A building form including a plurality of spaced channel members, inner wall forming sections between said channel members, and means on said channel members for removably supporting a horizontal beam for holding said channel members in alignment, outer wall forming sections spaced from said inner wall forming sections to define a mold cavity, and wires connecting said beam with a portion of said outer wall forming sections.

80 3. A building form including a plurality of spaced channel members, inner wall forming sections between said channel members, and means on said channel members for removably supporting a horizontal beam for holding said channel members in alignment, outer wall forming sections spaced from said inner wall forming sections to define a mold cavity, and wires connecting said beam with a portion of said outer wall forming sections, said wires being twisted midway between their points of connection and adapted to be severed upon the completion of the wall whereby the twisted portion is left in the wall for reinforcement of the same.

85 4. A building form including a plurality of spaced channel members, inner wall forming sections between said channel members, and means on said channel members for removably supporting a horizontal beam for holding said channel members in alignment, outer wall forming sections spaced from said inner wall forming sections to define a mold cavity, and wires connecting said beam with a portion of said outer wall forming sections, bolts carried by said channel members and extending inwardly into said mold cavity, a nut removably carried by the free end of each bolt, and wires passing around the vertical beams of said outer wall forming sections, and having their free ends secured to the respective nuts.

90 5. A building form including a plurality of equi-distantly spaced channel members, inner wall forming sections between said channel members, and means on said channel members for removably supporting a horizontal beam for holding said channel members in alignment, outer wall forming sections spaced from said inner wall forming sections to define a mold cavity, and wires connecting said beam with a portion

of said outer wall forming sections, bolts carried by said channel members and extending inwardly into said mold cavity, a nut removably carried by the free ends of each bolt, and wires passing around the vertical beams of said outer wall forming sections, and having their free ends secured

to the respective nuts, a portion of said wires and said nuts adapted to remain in the wall upon the completion of the same. 10

In testimony whereof I have affixed my signature.

HENRY C. RIESBOL.
